THREAD CLEANING DEVICE

Albert G. Osborne, Paterson, and Bertrand H. H.
Noble, Glen Rock, N. J.Original application August 23, 1935, Serial No.
37,460. Divided and this application April 30,
1936, Serial No. 77,078

3 Claims. (Cl. 28—70)

This invention relates to improvements in thread cleaning devices, the principal object of the invention being to provide an improved device of this character by means of which the entire surface of the thread will be cleaned in a single operation, this application being a division of our prior application Serial No. 37,460, filed August 23, 1935.

One of the objects of the invention is to provide a pair of slotted thread-cleaning members normally disposed in such relation to each other that their intersecting slots form a radially closed thread-cleaning opening, one of said members being movable relatively to the other to afford radial access to said opening thereby to permit a thread to be laterally inserted into the cleaning opening.

Other objects and advantages of the invention will be apparent as the description proceeds.

In the drawing accompanying this specification,

Fig. 1 is a perspective view of a preferred embodiment of a device constructed in accordance with the present invention;

Fig. 2 is a sectional view taken approximately on the line II—II of Fig. 1; and showing the movable parts at opposite limits of their movement in full and broken lines respectively; and

Fig. 3 is an enlarged detail sectional view illustrating the normal operating position of the cleaning members with relation to the thread.

In the form shown herein, the device comprises a base block 1^a carrying porcelain thread guides 3^a and 4^a which base-block is provided at its underside with a V-shaped recess by means of which it may be seated on the traverse rail of the winding machine, a slot 20 being provided for the passage of the usual holding bolt for securing it in place. Mounted on the block 1^a is a fixed, slotted cleaning head 21 of a well-known type, and cooperating therewith is a second slotted head 22 mounted for sliding movement transversely of the first head. The head 22 is pivoted at one end thereof to a lever 23, which is itself pivoted at one end to a lug 1^b formed on the base member 1^a. The head 22, at the end thereof opposite the lever, is elongated to form an arm 22^a which is pivotally connected to a pitman 24 pivoted to the base 1^a. A coil spring 25 is supported on a pintle carried by the base 1^a and is connected at one end to an extension of the pivot of the arm 22^a, as indicated at 26, Fig. 1, the opposite end of the spring being secured to the underside of the base member. The tension of the spring 25 thus normally maintains the slidable cleaning

head in the full line position shown in Figs. 1 and 2, in which position the intersecting slots of the cleaner heads form a square opening for the passage of the thread 18^a through the heads. For permitting the insertion of the thread into the cleaning opening, the lever 23 is operated to carry the slidable cleaner head to the position indicated in broken lines in Fig. 2, in which position the open end of the slot of the slidable member is in line with the open end of the fixed member 21, so that the thread after passing down through the slot of the fixed member will rest on the arm 22^a of the slidable member and upon release of the lever 23 the slidable cleaner head will be moved under tension of the spring 25 to the full line position shown in Figs. 1 and 2, thereby causing the thread to enter the slot of the slidable head. It will thus be seen that in this form of the device the thread will be cleaned on four sides. In order to limit the movement of the lever 23 under the influence of the spring 25, a stop plate 27 is secured to the base 1^a and provided with a lug extending into the path of movement of the lever, as shown clearly in Fig. 1. The slidable cleaner head is maintained in sliding contact with the fixed head by means of an L-shaped flat spring 28 the horizontal leg of which is secured by screws 29 to the base 1^a and the vertical leg is turned over into engagement with the side of the arm 22^a of the slidable cleaner head, as indicated in broken lines in Fig. 2.

Fig. 3 shows the cleaner heads 21 and 22 in section with the thread 18^a passing through the square opening formed by the intersecting slots, all of the parts being very much exaggerated in size.

From the foregoing it will be obvious that in the device herein described we have provided a thread cleaner in which a pair of cleaning members cooperate to form a square opening so as to engage the entire surface of the thread passing therethrough, and which opening is normally inaccessible radially thereof, so that the thread cannot leave the opening during the cleaning operation, nor can a thread be placed in position to be cleaned without first moving one of the cleaning members relatively to the other thereby to render the opening radially accessible.

While we have described in detail the embodiment of the invention herein disclosed, it is to be understood that we do not thereby limit our invention to the precise features of construction shown in the drawing, as we are aware that many mechanical changes and modifications may be made therein without departing from the spirit

and scope of the invention as set forth in the claims hereto appended.

Having thus described our invention, what we claim is:

- 5 1. A thread-cleaning device comprising in combination a base, a cleaning member secured on said base and having an elongated open-ended slot, a cleaning member pivotally supported at its opposite ends in transverse juxtaposition to said first member, said pivotally supported member also having an elongated open-ended slot, means for normally maintaining the pivotally supported member at one extremity of its pivotal movement, and means for moving said member to the opposite extremity of its movement thereby to bring the open ends of the slots into position to afford access to both of said slots.
- 10 2. A thread-cleaning device comprising in combination, a base, a cleaning member secured on said base and having an elongated open-ended slot, a cleaning member supported for sliding movement transversely of said first cleaning member and having an elongated open-ended slot, tension means acting on said slideable member for maintaining it laterally in juxtaposition to said first member, tension means acting on said slideable member longitudinally thereof normally to maintain it at one extremity of its sliding movement with its slot intersecting that of
- 15
- 20
- 25
- 30

its companion member thereby forming a radially closed cleaning opening, and manually operated means for moving said pivoted member to the opposite extremity of its movement against the action of said tension means thereby to bring the open ends of the slots into position to afford access to both of said slots.

3. A thread cleaning device comprising in combination, a base, a pair of cleaning members each provided with a longitudinally extending slot open at one end, one of said members being fixed on said base, a pair of links pivoted at one end to said base at opposite sides of said fixed member, the other cleaning member being pivoted at its opposite ends to said links whereby said member is slidably maintained in transverse position relatively to said fixed member, means for limiting the pivotal movement of said links in both directions, automatically operative means for maintaining the shiftable member at one extremity of its movement whereby its slot intersects that of the fixed member and forms therewith a radially closed thread-cleaning opening, and means for moving said shiftable member to the opposite extremity of its movement thereby to carry its slot out of intersecting relation with that of the fixed member and permit access to the open ends of both slots.
